CLAIM

I claim the ornamental design for a disposable plate, as shown and described.

DESCRIPTION

FIG. 1 is a perspective view of a disposable plate of the present claimed design;

FIG. 2 is a top plan view of the disposable plate of FIG. 1; FIG. 3 is a side view of the disposable plate of FIG. 1, all other side views being identical thereto;

FIG. 4 is a bottom plan view of the disposable plate of FIG. 1; and,

FIG. 5 is a cross-sectional view of the disposable plate taken along lines 5—5 of FIG. 1.

Features shown in broken lines in the drawings form no part of the claimed design.
